DESCRIPTION

FIG. 1 is a top view of a four finger cosmetic applicator glove showing my new design with the glove in a first condition in which a bag is contained within a bag pouch provided on the top of the glove;

FIG. 2 is a front view thereof in the first condition;

FIG. 3 is a right side view thereof in the first condition;

FIG. 4 is a left side view thereof in the first condition;

FIG. 5 is a perspective view thereof in the first condition;

FIG. 6 is a perspective view of the four finger cosmetic applicator glove showing my new design with the glove in a second condition in which the bag has been removed from the bag pouch;

FIG. 7 is a top view thereof in the second condition;

FIG. 8 is a bottom view thereof in the second condition;

FIG. 9 is a bottom view of the four finger cosmetic applicator glove showing my new design with the glove in a third condition in which the bag which has been removed from the bag pouch has been positioned over the four fingers of the glove; and,

FIG. 10 is a top view thereof in the third condition.
